C. W. COOKE

DISPENSING CAP FOR BOTTLES

Filed Aug. 6, 1926

FIG. 1.

FIG. 2.

FIG. 3.

Inventor
Conway W. Cooke

UNITED STATES PATENT OFFICE.

CONWAY W. COOKE, OF WASHINGTON, DISTRICT OF COLUMBIA, ASSIGNOR OF ONE-HALF TO WALTER M. MACNICHOL, OF WASHINGTON, DISTRICT OF COLUMBIA.

DISPENSING CAP FOR BOTTLES.

Application filed August 6, 1926. Serial No. 127,636.

The present invention relates particularly to dispensing caps for bottles containing carbonated liquid, such as ginger ale and the like. When mixing such a liquid with a base, it is well recognized that a much more palatable drink results if the bottle containing the liquid is well shaken and the liquid forcibly discharged in a fine stream under the impetus of the liberated gas.

10 The cap according to my invention is designed to be applied to a standard bottle subsequent to removing the sealing cap, and while the new cap is readily applicable and removable, it is so constructed as to form 15 an air tight and rigid connection with the neck of the bottle when in position for operation. Upon adjusting the cap the bottle may be shaken to liberate the gas, and valve means are provided so that subsequently the liquid may be dispensed as 20 needed.

One embodiment of my invention is illustrated in the accompanying drawings, this embodiment being merely illustrative and in 25 no sense restrictive. In the drawings Figure 1 is a top plan view of the new cap; Figure 2 is a vertical section on the line 2-2 of Figure 1, the cap being shown in connection with the neck of the bottle, and Figure 3 shows the cap as seen from beneath.

Referring to drawings, 10 represents the main body of the cap, which, as may be readily seen from Figure 2, is cupped to produce an annular flange 11, the margin of which is designed to fit around the bead 12 of a standard bottle. For somewhat more than half of its circumference the flange is extended downwardly, as at 13, and bent to fit under and grip the bead 12. Elements 35 10, 11, and 12, just described, are preferably formed integrally of suitably heavy spring metal, and for ease of manipulation the extremities 14 of flange 13 may be bent outwardly (beyond their semi-circumferential 40 extent), and slit inwardly, as at 15 (Figures 2 and 3).

Seated in the upper portion of cap 10 is a washer or packing element 16 of such configuration as to secure a snug fit. The element 50 16 is preferably of rubber, this material having the necessary resiliency and durability, although any other suitable material may be used. The mass of this washer is such that, when the cap 10 is adjusted in 55 operative position, its lower margin will be

compressed to form an air tight packing. As shown in Figure 2, washer 16 is provided with an axial bore 17 registering with a perforation 18 in cap 10. The bore 17 is enlarged as at 19 and this enlargement 60 communicates by a duct 20 with a liner and spout 21 rigidly secured in an aperture in the cap. The inner cross section of element 21, or at least of its orifice, is very small so as to deliver an extremely fine stream. The 65 inner portion of element 21 serves to hold washer 16 in proper position and to prevent the blocking of the duct upon compression of the washer.

A valve disc 22, mounted on a stem 23 70 which extends upwardly through bore 17 and perforation 18, serves to cover enlargement 19. Stem 23 has a button 24 mounted on its outer extremity, and interposed between the button and cap 10 is a return 75 spring 25.

It will be seen that under normal conditions disc 22 will prevent the escape of any gas through duct 20 while upon depression of button 24, duct 20 will be opened, and 80 upon inversion of the bottle, the contained liquid will be forcibly discharged.

It is to be emphasized that the cap according to my invention is adaptable for repeated application to standard beverage bottles—in other words, it is a durable accessory. I also call attention to the fact that the attachment means are substantially positive; that is to say, pure friction is not relied upon, but a positive gripping action is 90 present. It will also be noted that the pressure within the bottle will tend to seat the valve disc the more securely.

While I have necessarily described my invention in some detail, it will be recognized 95 that various changes within the range of mechanical skill will suggest themselves to those skilled in the art. It is to be understood, however, that I do not limit myself except as in accordance with the following 100 claim.

I claim:

A cap for charged-beverage bottles of the type having a top peripheral bead, said cap comprising depending opposed gripping 105 means, said gripping means being engageable under opposite portions of said bead upon forced movement of said cap substantially parallel to the bead, whereby said cap is retainable in operative relation to said bot- 110
